UNITED STATES PATENT OFFICE

2,442,107

ABRASIVE AND POLISHING TAPE

Maurice G. L. Wallich, Vancouver, British Columbia, Canada, assignor, by mesne assignments, to Paper Strap, Inc., Portland, Oreg., a corporation of Oregon

Application September 25, 1946, Serial No. 699,325

2 Claims. (Cl. 51—185)

1

The present invention relates to a new and improved abrasive and polishing tape.

The abrasive or polishing strips now available usually comprise a single layer of paper, cloth or the like with the abrasive or polishing grains secured to one or both sides by means of a suitable binder. Paper is preferred as a backing sheet because of its lower cost. While the abrasive coated paper strips are satisfactory for most sanding or polishing applications they are not particularly useful for the finishing of rounded surfaces, particularly spherical or other surfaces of compound curvature, primarily because paper does not possess sufficient give or stretch for the normally flat strips to conform to such rounded surfaces.

It is an object of the present invention to provide a new and improved abrasive coated paper in tape or roll form which is inexpensive and strong and is particularly useful for sanding, polishing or buffing rounded surfaces.

A further object of the invention is to provide a new and improved sandpaper comprising a backing member in the form of a folded paper tape so constructed as to cushion the sanded surface and to assure a firm, even contact of the abrasive coated side of the tape with rounded or irregularly curved surfaces.

In accordance with the present invention there is provided an abrasive or polishing tape comprising a backing member obtained by folding the opposite marginal edge portions of a strip of relatively thin and tough paper over upon itself a plurality of times. The folded edge portions extend on the same side of the strip, the width of each folded portion being slightly less than one-half the total width of the finished tape whereby the folded portions lie flat in a nonoverlapping relation against the central strip portion. The folded tape is provided with a multiplicity of closely adjacent creases or crimps extending through all of the layers thereof whereby the folds are set and the tape rendered relatively flexible or pliable. The folded side of the tape is then provided with a layer of abrasive or polishing material adhesively secured thereto by means of any of the numerous adhesives employed in the manufacture of sandpaper and the like. The resultant product comprises two parallel abrasive coated surface portions joined at their outer edges by means of the central strip portion forming the principal backing portion of the tape and a plurality of cushioning layers of paper sandwiched between the abrasive coated portions and the central strip portion.

2

Additional objects and advantages of the invention will become apparent from the following description thereof and by reference to the accompanying drawing.

In the drawing, Figs. 1 and 2 are perspective views illustrating the opposite sides of an abrasive tape constructed in accordance with one form of the present invention; Fig. 3 is a perspective view illustrating a further modification of the invention; Fig. 4 is a fragmentary view partly in section illustrating a typical application of the abrasive tape of the invention, and Fig. 5 is an enlarged cross sectional view taken along line 5—5 of Fig. 4.

Referring to Figs. 1 and 2, there is shown a section of abrasive tape as comprising an elongated strip of relatively thin tough paper, such as kraft paper, and which has each of its opposite marginal edge portions folded over upon itself a plurality of times throughout its entire length. These folded portions 11 and 12 are arranged on the same side of the tape for reasons as will subsequently appear. In order to provide the desired tensile strength for the tape, the opposite edge portions are folded over preferably not less than three times, in which case four thicknesses of paper occur at each edge. It will be noted that the raw edge of the strip of paper from which the tape is formed is thus arranged within each folded portion of the product so that only folded or doubled edges of paper extend along the edges of the two folded portions 11 and 12 of the product to provide maximum strength and toughness thereto for resisting any tendency for the tape to be torn through. It will be noted also that the folded edge portions 11 and 12 are each about one-half the width of the finished tape in order that the two folded edge portions will lie flat, that is, in a substantially touching but nonoverlapping relation against the backing portion 13 of the paper strip extending therebetween.

In the modification illustrated in Fig. 3, the opposite edge portions 11 and 12 are folded upon themselves a plurality of times but in a somewhat different manner than in the previously described form. However, in both modifications only folded or doubled back edges of paper extend along the flat outer faces 16 and 17 of the folded edge portions 11 and 12.

Since the opposite edge portions 11 and 12 are folded over a plurality of times, the tape will initially be inherently relatively stiff and the edge portions will have a natural tendency to unfold. In order to render the tape relatively flexible and pliable and also to set the folds, a continuous suc-

cession of adjacent creases are formed transversely and throughout the full length thereof, each of the creases being furthermore formed in all of the superimposed layers of paper of each of the folded edge portions. This can be accomplished by drawing the tape through a plurality of relatively sharp bends in opposite directions such as over a number of suitably arranged, relatively small diameter rods or rollers whereby, due to the difference in radius of curvature between the inner and outer layers of the folded tape, buckling occurs with the resultant formation of a multiplicity of creases on both front and back sides of the tape and as a result the tape is rendered relatively pliable and the folds are compressed and firmly set. The creases thus formed are indicated in Figs. 1 and 2 at 14.

As an added result of the creasing of the various layers, the cushioning effect of the intermediate layers of paper in the folded portions 11 and 12 is also increased.

The coating of abrasive or polishing material can be applied to the outer surfaces 16 and 17 of the folded portions 11 and 12 respectively either before or after the creasing operation. Any of the usual binders can be employed for securing the abrasive or polishing material, examples of such binders being the various cellulose derivatives, such as ethyl cellulose, cellulose esters, etc., phenolic resins, alkyl resins, glue or suitable mixtures of one or more of these adhesive materials with or without modifiers, plasticizers, etc. Likewise, the invention is not limited to any particular abrasive material, sand, alumina, emery dust, and carborundum being mentioned merely as representative of the class of abrasive and polishing materials which can be employed, the selection of a specific material depending on the intended use of the tape.

The finished abrasive or polishing tape is particularly suited for the finishing of rounded surfaces first because of the fact that it will fold longitudinally along a line between the two folded edge portions 11 and 12 so that more uniform contact of the tape with a curved or spherical surface of a work piece is possible, and secondly, because of the fact that when the abrasive coated side of the tape is brought into contact with a rounded surface, the central backing portion 13 takes up most of the strain resulting from holding the tape in contact with the surface while the various layers of paper in the folded end portions 11 and 12 buckle due to the difference between the radius of curvature of these layers and backing portion 13, the buckled portions causing a cushioning of the abrasive coated surfaces so that pressure of the tape on the work piece is more uniformly and evenly distributed over the entire surface area of the tape which is in con-

tact with the work piece. As a result, spotty or uneven sanding or polishing of rounded surfaces is largely eliminated. For best results the tape should be provided in overall widths not exceeding about one inch, and preferably of a width of from about $\frac{3}{8}$ to $\frac{3}{4}$ inch. The manner in which the tape functions in the sanding of rounded surfaces is illustrated in Figs. 4 and 5 where numeral 21 indicates a work piece in the form of a chair rung comprising a plurality of spherical sections 22, the rung being rotated about its longitudinal axis during the finishing thereof with the abrasive tape held at right angles to that axis.

When thus used, the tape folds along its center line to bring faces 16 and 17 into engagement with the rounded surface while the crinkling or buckling of the layers of paper forming or adjacent to the faces 16 and 17 plus the cushioning action of the inner layers results in a firm and uniform contact of the abrasive coated surfaces with the curved surface of the work piece.

Having described the invention in what are considered to be certain preferred embodiments thereof, it is desired that it be understood that the specific details shown and described herein are merely illustrative and that this invention may be carried out by other means.

What I claim is:

1. A flexible abrasive coated tape comprising a flat strip of relatively thin tough paper, each of the opposite edge portions of said strip being folded over upon itself a plurality of times, the folded edge portions extending in nonoverlapping relation and substantially meeting along the center line on the same side of said strip, and a layer of abrasive material adhesively secured to the surfaces of said folded edge portions.

2. A flexible abrasive coated tape comprising a flat strip of relatively thin tough paper, each of the opposite edge portions being folded over upon itself, the folded edge portions meeting substantially along the center line on the same side of said strip and a layer of abrasive particles bonded to the outer surfaces of said folded edge portions.
